UNITED STATES PATENT OFFICE.

OSCAR MURISIER, OF ALEXANDROWSKY, NEAR ST. PETERSBURG, RUSSIA,
AND PERCY CARLYLE GILCHRIST, OF PALACE CHAMBERS, WESTMINSTER,
ENGLAND; SAID MURISIER ASSIGNOR TO SAID GILCHRIST.

JUNCTION OR SEPARATOR LINING FOR OPEN-HEARTH FURNACES.

SPECIFICATION forming part of Letters Patent No. 329,937, dated November 10, 1885.

Application filed May 4, 1885. Serial No. 164,373. (No specimens.)

To all whom it may concern:

Be it known that we, OSCAR MURISIER and PERCY CARLYLE GILCHRIST, respectively a citizen of the Swiss Republic, residing at Alex-
5 androwsky, near St. Petersburg, Russia, and a subject of the Queen of Great Britain, residing at Palace Chambers, Westminster, Eng-
land, have invented a certain new and useful
10 Improvement in Junction or Separator Lin-
ings for Open-Hearth Furnaces, of which the
following is a specification.

In the manufacture of steel in the Siemens
or open-hearth furnace by what is known as
the "basic" or "Thomas Gilchrist" process,
15 much difficulty has been experienced when
the silica roof and sides have been allowed to
rest directly upon the basic hearth, as in such
case the silica combines with the basic mate-
rial and rapidly melts away, bringing down
20 with it the sides and ports of the furnace.

The object of our invention is to remedy
this defect, and to this end we employ chrome
ore made plastic with tar as a separator or
junction between the basic and silicious mate-
25 rials, such junction being preferably above
the slag-level. Such mixture, we find, does not
flux with either the basic or silica materials,
and may be readily put in place by ramming
in the ordinary manner, or may be used in the
30 form of bricks prepared by mixing the chrome
ore with just sufficient tar to make the mass
plastic, such mass being then molded under
pressure into the form of bricks, which may
or may not receive a preliminary firing before
35 being placed in position. The chrome ore
and tar junction (whether rammed *in situ* or
used in the form of bricks) need only be of a

few inches in thickness, and will rest directly
upon the basic material, while the silica will
rest directly upon it. 4c

We are aware that it has been before pro-
posed to use chrome ore and oxide of chromium
for lining furnaces, as in United States Letters
Patent No. 308,984, such lining being highly
resistant and interposed between the bath of 4.
metal and the ganister or other lining, and
covering the whole of such lining; but such
materials have not, so far as we know, been
mixed with tar and used simply as a junction
or separator, and 5

What we therefore claim, and desire to se-
cure by Letters Patent, is—

1. A mixture of chrome ore and tar, com-
pounded substantially as set forth, for use in
separating or forming the junction between 5
the basic and acid portions of the linings of
metallurgical furnaces.

2. A furnace-lining composed of a basic bot-
tom, basic sides, and acid roof, and a belt of
a mixture of chrome ore and tar interposed 6
between the roof and sides, as set forth.

In witness whereof we have hereunto set our
hands, each in the presence of two subscribing
witnesses.

OSCAR MURISIER.

PERCY CARLYLE GILCHRIST.
